Attorney

Patented Feb. 26, 1929.

UNITED STATES PATENT OFFICE.

EMIL G. GASSEN, OF CHICAGO, ILLINOIS.

PARTITION FOR BANKS, OFFICES, AND OTHER SIMILAR PLACES.

Application filed February 25, 1927. Serial No. 170,820.

This invention relates to a partition which is adapted to be substituted for the grille, partitions which are often installed in banks, offices and other places to separate an outer space or room from the space or room in which the employees are allotted to work.

Among the objects of the invention is to obtain a partition whereby the employees of the establishment where it is installed will be protected from assault and injury from a person or persons in the space or chamber provided for those having business to transact, or desirous of receiving money in exchange for money of a different denomination, for checks, from pay rolls, or in the payment of bills presented. A further object is to provide a partition which will afford the employees positioned on one side thereof means to view so much of the space and of the persons on the other side thereof as is necessary to enable said employees to intelligently and expeditiously perform any and all duties incumbent on or desirable for them to perform, while protected as recited. 25 A further object is to obtain a partition which is economically made and installed, of good appearance, durable, and the movable members associated therewith are readily understood and easily operated.

Fig. 1 is a front elevation of a portion of the partition embodying my invention and of a movable member associated with and forming a part thereof:

Fig. 2 is a vertical section of the portion of the partition which is illustrated in Fig. 4, on line 2—2 of said figure viewed as indicated by arrows; and

Fig. 3 is a rear elevation of said portion of the partition.

A reference character used to designate a given part indicates said part throughout the several figures of the drawing wherever the same appears.

This partition preferably extends from a floor to a height of approximately eight feet above said floor and may be made principally of sheet metal.

1 represents the body of the partition, 2 a portion of said body representing a mop board, and 3 a portion representing a cornice.

In the constructions illustrated in Figs. 1, 2 and 3 the body, 1, of the partition is provided with table 7^a on the front side thereof, and with receptacle 14 on the back. The bottom 15 of receptacle 14 is in substantially the same plane as table 7^a; and the partition is

provided with aperture 16 extending a suitable distance upward from said plane. 17 represents a movable door adapted to close the aperture 16. 18 represents a runway or 60 guide in which door 17 slides when operated. It will be observed that the forward edge of bottom 15 is set back from partition 1 so that door 17 moves between said edge and said partition. 19 represents a cover to receptacle 14, and 20 represents a pivot by means of which said cover is hinged to partition 1. 21 represents a handle pivotally mounted on cover 19. 22 represents a catch or hasp on handle 21, and 23 an abutment on the outside of the rear wall, 24, of receptacle 14. When cover 19 is in a plane to close or cover receptacle 14 the weight of handle 21 causes catch or hasp 22 to engage with abutment 23 and lock said cover from being raised by a 75 person in front of the partition. When cover 19 is to be raised or turned on its pivot 20, by an employee the handle 21 is grasped and turned on its pivot, thereby catch or hasp 22 is released from engagement with abutment 23, and continued raising of said handle raises said cover.

When a package of any kind is to be discharged from back of partition 1 through aperture 16, to be received by a person or 85 persons in front of the partition, the cover 19 is raised in the manner described, said package is deposited in receptacle 14, the cover is closed, and clasped, and door 17 is moved from said aperture.

The mechanism which I prefer to use to move door 17 from closing aperture 16 and to return it to position closing said aperture, and to lock it closed against a person in front of the partition includes the following recited 95 members, operating as hereinafter described.

25 represents a lever and 26 a pivot which forms the fulcrum of said lever. 27 represents a flexible connection to lever 25 adjacent to one end thereof and attached to levers 28, which are pivotally mounted at 29 on said door 17. 30 represent catches or hasps on levers 28, and 31 abutments with which the catches or hasps are engageable when the door 17 is in position to close the aperture 16. 100 32 represents a spring which is attached at one end to the door 17 and at the other end to levers 28. Spring 32 yieldingly holds catches or hasps 30 in engagement with abutments 31 and locks the door closed against 110 a person in front of the partition.

To automatically return door 17 to position

closing aperture 16 I prefer to use weights, represented at 33, vertically movable in guides or runways 34, and connected by flexible cords or cables 35 to the door. The cords or cables 35 extend over the rotatively mounted pulleys 36.

To open door 17 it is necessary to step on lever 25 and force the end thereof to which connection 27 is attached, downward. The 10 initial downward movement of said end of lever 25 turns levers 28 on pivot or fulcrums 29, to release catches or hasps 30 from abutments 31, and continued downward movement of said end moves the door 17 down, causing 15 it to slide in runways 18.

On releasing lever 25 from its operated position the weights 33 automatically move door 17 and the ends of lever 25, up, closing aperture 16 and permitting spring 32 to turn 20 levers 28 and cause catches or hasps 30 to engage with the immovable abutments 31, and lock said door closed.

Above door 17 and aperture 16 there are placed aperture 11 and shield 13, to enable 25 the employee in charge of the door to identify the person or persons in front of the partition who are in position to receive the package.

I claim:

1. A partition provided with an aperture, a

shelf rigidly attached to said partition on one side thereof and a receptacle on the other side of said partition, means to close said aperture, said means to close forming one side of said receptacle, and an additional side of said receptacle consisting of a movable member, in combination with means to control said means to close said aperture, and means to lock said movable member in place to form said additional side, said means to lock arranged to be controlled by a person on the same side of the partition as said receptacle. 30
35

2. A partition provided with an aperture and with an additional aperture, a shelf rigidly attached to said partition on one side thereof and a receptacle on the other side of 40 said partition, means to close said first named aperture and said means to close forming one side of said receptacle, and an additional side of said receptacle consisting of a movable member, in combination with a shield to said 45 additional aperture, means to control said means to close said aperture and means to lock said movable member in place to form said additional side, said means to lock arranged to be controlled by a person on the same side of 50 the partition as said receptacle. 55

EMIL G. GASSEN.
